PIANO

Edward G. Kurtz, Nashville, Tenn.

Application October 20, 1953, Serial No. 27,243

Term of patent 7 years

(Cl. D56—9)

To all whom it may concern:

Be it known that I, Edward G. Kurtz, a citizen of the United States of America, residing at Nashville, Davidson County, Tennessee, have invented a new, original, and ornamental Design for a Piano, of which the following is a specification, reference being had to the accompanying drawing forming a part thereof, and in which the figure is a perspective view of a piano, showing my new design.

I claim:

The ornamental design for a piano, as shown.
